UNITED STATES PATENT OFFICE.

LAWRENCE E. ROBINSON, DECEASED, LATE OF COFFEYVILLE, KANSAS, BY EDITH A. ROBINSON, ADMINISTRATRIX, OF COFFEYVILLE, KANSAS.

OIL-WELL SWAB.

Application filed August 12, 1921. Serial No. 491,718.

To all whom it may concern:

Be it known that I, EDITH A. ROBINSON, a citizen of the United States, residing at Coffeyville, Montgomery County, Kansas, declare that LAWRENCE E. ROBINSON, deceased, invented certain new and useful Improvements in Oil-Well Swabs; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to oil well swabs and particularly to a novel construction of swab which will possess certain advantages not inherent in swabs now generally employed.

For example, the invention involves the inclusion of means for unloading the oil when the column of oil is greater than the capacity of the elevating means for raising it.

Another object of the invention is to provide means whereby the maximum depth below the surface of the oil at which the swab will be effective to raise the amount or weight of oil from the well can be determined.

Novel arrangements of packing or lift rings are also provided to prevent leakage of the oil on the upstroke of the swab, the valve or lift rings being so arranged that the swab can be conveniently lowered into the well preparatory to raising the column of oil, this function being effective with the minimum of friction.

It is also the purpose of the invention to generally improve the construction of oil well swabs to improve the operating performance of the same in a novel and inexpensive manner.

With these objects in view and in order to improve generally the type of device above enumerated, the invention consists in a certain novel arrangement of parts and combinations of parts, all of which will be specifically described hereinafter, reference

being had to the accompanying drawings, in which

Fig. 1 is an elevational view of a swab constructed in accordance with my invention being lowered into an oil well casing, the oil well casing being shown in section.

Fig. 2 is a similar view of the swab moving upward with the oil well casing shown in section.

Fig. 3 is a vertical, longitudinal, sectional view through the swab and oil well casing.

Fig. 4 is a perspective view of a lift ring or valve.

Fig. 5 is a cross sectional view through a modified form of lift ring, and

Fig. 6 is a sectional view on the line 6—6 of Fig. 4.

The oil well casing 1 may be of any preferred construction and may be introduced into the oil well in the usual way. The oil well swab is shown as consisting of an elongated tubular member 2 having an internally threaded upper end 3 and an externally threaded lower end 4. Between the ends of the tubular member 2 is an integral collar 5 and above it is a plurality of inlet openings 6. Above the collar 5 is a longitudinally slideable sleeve 7, the inner face of which is spaced away from the outer face of the tube 2 by flanges 8 and 9 to reduce the friction when the sleeve slides upon the tube 2. The inner lower face of the sleeve 7 is threaded at 10 to receive a ring valve 11 adapted normally to rest upon the collar 5 and to close off communication between the well casing and the inlet openings 6.

The upper end of the sleeve 7 is provided with internal threads 12 and external threads 13. The internal threads receive a packing ring 14 to hold the packing 15 between it and the flange 8 in place. The external threads 13 receive the adjusting and lock collars or nuts 16 and 17, preferably provided with spanner openings whereby they can be adjusted upon the sleeve 7 and these collars co-operate with similar collars 18 and 19 to retain valve or lift rings 20 between them and in co-operative relation with the sleeve 7.

The lift rings or valves 20 are preferably

constructed as shown in Fig. 4, consisting of segments 21, 22 and 23, each of which is provided with an overlapping portion or tongue 24 and a shouldered or cut-away portion 25 whereby the ends of the segments will overlap one another. Each segment is shown as comprising an angle-shaped member to receive a filler 26, preferably of rubber or rubber and fabric, the outer edge 27 of which may slightly overlap the angle-shaped holder so that the edge 27 may bear against the inner face of the oil well casing. The segments are held together by a continuous ring member 20' having upstanding pins 33, which project through slots in the filler 26 and through slots in the overlapping portions of complementary segment members, the angles and the ring 20' forming a channel for each segment, within which the filler 26 is received.

The inner circumference of each ring is inclined, as at 28, to ride upon a cone 29, there being a cone 29 for each packing ring or valve and each cone is the same width as its ring so that the ring will have relative movement with respect thereto, the rings being supported by the collar 18. The lower cones are supported by the shoulder 30 on the sleeve 7 and each upper cone is supported by the cone below it.

As heretofore explained, there is means provided whereby the lift rings or valves 20 may have movement independent of the sleeve so that they can contract and expand, as will be clearly seen in Fig. 4, it being observed in that figure that the tongues 24 are slightly spaced from the abutting edges of the shoulders or recesses of the complementary ring so that they may expand and the segments are all held together by the overlapping tongues 31, which are provided with slots 32 to receive the pins 33 in a complementary segment, the slots allowing for the necessary radial expansion and contraction.

The lower end of the tube 2 receives a threaded collar 34, on which rests one end 35 of an expansion spring 36, the upper end of which bears against the face 37 of the sleeve or hood 38, which extends below the bottom of the tube 2 and carries a plug valve 39, which is adapted to seat upon the seat 40 threaded into the tube 2 at 41. Therefore, the spring will tend to maintain the valve 39 closed or seated.

The upper internally threaded portion 3 of the tube 2 carries a tool rod coupling 42, having a threaded portion 43 to engage into the tool rod and said coupling is hollow, being provided with outlet ports 44, as clearly seen in Fig. 3.

When it is desired to determine the flow of oil into the oil well casing, the swab is lowered thereinto in the usual way. The slight friction of the perimeters 27 of the fillers or packing rings 26 with the inner

face of the oil well tube 1 will cause the rings to slide up on the faces of their cones and also raise the sleeve 7 on the tube 2, the upward movement of the sleeve being limited by the collar 45 on the coupling 42. The sleeve 7, however, can rise far enough to cause the ring valve 11 to uncover the ports 6, allowing oil below the packing rings 20 to enter the ports 6, pass through the tube 2 and exit through the discharge ports 44 so that the oil will be above the valve or packing rings 20.

When the swab has been lowered into the oil at approximately the correct depth, the operating means will be operated so as to raise the swab. The initial upward movement of the swab will cause the rings 20 to move downwardly, carrying with them the sleeve 7, causing the valve ring 11 to close off the ports 6 so that the oil may be trapped above the rings 20 and the column of oil supported by said rings can be raised to the top of the oil well. If, by chance, the column of oil is greater than can be handled by the elevating means, that is, if it is so heavy that the elevating means at the top of the oil well cannot raise it, the hydrostatic pressure on the plug valve 39 will preponderate over the spring 36 so that the valve 39 will unseat and the oil will exhaust from ports 44 through the opening closed by the plug valve 39 until the swab is raised to a sufficient height within the oil well casing to allow the spring 36 to preponderate over the hydrostatic pressure to close the valve 39. Then the column of oil above the packing or valve rings 20 can be raised to the top of the oil well and measured.

After a given time the swab can again be lowered into the oil well and the column above the determined level can be drawn from the oil well and a proper estimate made of the rate of flow of the oil within the well.

It will be observed that the valve 39 is an overload or unloading valve, which will free the swab of overload in the event that it has been lowered too deep into the well before the upward stroke takes place.

It will also be observed that by adjusting the nut or adjustable collar 34 the spring can be set to operate at varying depths below the level of the oil and that the construction of the ring 20 is such that the swab can be lowered into the well with the minimum of friction and with reasonable assurance of perfect operation.

It will be observed also that the channel members for the rings 20 are metal so that there will be a metal surface rubbing against a metal surface when the ring segments expand and contract, which is a material advantage over the forms of rings in which rubber or resilient material rubs over like material, because in the latter case, the friction is so great as to prevent satisfactory

performance and since the inner faces of the rings 20 are also metal to ride on the metal cones, they will freely slide either upward or downward, dependent upon the direction 5 of movement of the swab.

By reference to Figs. 1, 2 and 3, it will be seen that the cap or sleeve 38 is in the form of a cage, the upper portion of which is connected to the lower portion or ring 38' 10 by the spaced bars 38" so that a cage is formed, which will allow the oil to readily escape through the openings 46, when the valve 39 moves to unloading position. The packing ring 14 will efficiently hold the 15 packing in place and if desired, packing may be put into the space 47 but in all instances this will not be necessary.

Any suitable resilient material may be employed in the channel members for the rings 20 but I prefer to use pure rubber or a rubber and fabric composition.

Attention is called to the fact that the rings 20 constitute a piston which will act substantially like a pump piston when the 25 swab is raised to elevate the oil above the swab and within the casing 1 and that in view of the fact that the valve 11 will be seated to close the ports 6, the oil cannot escape below the piston even though the 30 ports 44 are open unless the overload relief valve 39 is unseated due to the hydrostatic pressure of the oil above the piston.

The plates 48 are vulcanized into the segments to provide wear plates or anti-friction 35 surfaces for the abutting faces of the segments when they expand and contract.

From the foregoing it will be apparent that the device is simple in construction, inexpensive to manufacture and admirably 40 adapted to serve the purpose for which it is intended.

What I claim and desire to secure by Letters Patent is:

1. An oil well swab comprising a central 45 tubular member having an inlet and an outlet, a sleeve slidable upon the central member, means carried by the sleeve for valving the inlet, and oil lift rings carried by the sleeve, the rings being interposed between 50 the inlet and the outlet.

2. An oil well swab comprising a central 55 tubular member having an inlet and an outlet, a sleeve slidable upon the central member, means carried by the sleeve for valving the inlet, and radially expansible and contractible oil lift rings carried by the sleeve, the rings being interposed between the inlet and the outlet.

3. An oil well swab comprising a tubular 60 member having an inlet port and an outlet port, oil lift rings carried by the member and positioned between the inlet and outlet ports in said member, means for automatically valving one set of ports, and an overload relief valve carried by the tubular mem-

ber and adapted to open when the hydrostatic pressure above the swab preponderates over the closing tendency of said valve.

4. An oil well swab comprising a central 70 tubular member having an inlet port and an outlet port, a longitudinally movable and radially expansible piston carried by the exterior of the tubular member, inlet port valving means for the tubular member movable in response to movement of the piston, and a spring supported overload relief valve carried by the lower end of the tubular member.

5. An oil well swab comprising a central 75 tubular member having an inlet port and an outlet port, a longitudinally movable and radially expansible piston carried by said member, a valve for the inlet port in the tubular member movable in response to movement of the piston, and an unloading 80 valve carried by the tubular member.

6. An oil well swab comprising a tubular 85 member having an inlet port and an outlet port, a sleeve slidable on the tubular member, cone rings on the sleeve, sectional rings mounted about the cone rings and comprising segments slidable on the cone rings to move them outwardly, and a valve for opening and closing the inlet port in the tubular member in response to movement of the 90 sleeve.

7. An oil well swab comprising a central 95 tubular member having an outlet port at its upper end, an inlet port near its middle portion, a sleeve slidable upon the tubular central member and having a portion movable over the inlet port near its middle portion to close said inlet port, and a overload relief valve carried by the lower end of the tubular member and adapted to open when 100 the hydrostatic pressure above the valve preponderates over the closing tendency of said valve.

8. An oil well swab comprising a tubular 105 member, cone rings supported on the tubular member, and piston rings slidable on the cone rings, said piston rings comprising segments and means for slidably connecting the segments together.

9. An oil well swab piston ring comprising 110 a plurality of segments, each of which consists of a channel having a tongue for overlapping a portion of an adjacent segment, yielding material in the channel, and means for connecting the overlapping tongue of one segment to the body portion of a complementary segment.

10. An oil well swab piston ring comprising 115 a plurality of segments, each of which consists of a metallic channel connected to a complementary segment, and yielding material in the channel, the perimeter of which extends slightly beyond the outer edge of the channel.

11. An oil well swab comprising a tubu-

41
lar member having an inlet port at its middle portion and an outlet port at its upper end, oil lift rings slidable on the tubular member and having means for covering and uncovering the inlet port, and an overload relief valve carried by the tubular member at its lower end and adapted to open when

the hydrostatic pressure above the swab pre-
ponderates over the closing tendency of the
valve.

10

In testimony whereof I affix my signature.
